Thurlow E. McFall, Sparta, Mich., assignor to
Michigan Arcraft Company, Sparta, Mich., a
corporation of Michigan

Application February 20, 1939, Serial No. 257,343

10 Claims. (Cl. 311—67)

This invention relates to tables. In rooms where space is restricted it is very desirable that a table in such room may be operated so as to take up a relatively small amount of space when it is not in use, but at the same time be available for use as a table having a considerable amount of horizontal top surface at the times when needed. The present invention is directed to a structure which when used as a table presents a circular table top with a horizontal upper surface, and when not in use can be operated to occupy approximately one-quarter of the space which it occupies as a table, and also which may be located at a corner of a room where it may serve the purpose of a corner stand or desk.

My invention is concerned with producing a table of the character described which can be readily changed from one condition to the other and which, when serving either as a table or a corner desk, will be strong and sturdy and fully capable of sustaining the service to which it is subjected. A further object of the invention is to provide a novel construction for the purposes stated, which is practical for economical and commercial production.

The invention may be understood from the following description of a preferred embodiment thereof, taken in connection with the accompanying drawings, in which:

Fig. 1 is a perspective view showing the structure when it has been retracted to its smaller space occupying position and in which it may be located at a corner of a room.

Fig. 2 is a plan view of the construction shown in Fig. 1 at the time of the completion of the first steps in converting the structure into a table having a horizontal circular top.

Fig. 3 is an under plan view of the structure when it has been completely converted into a table.

Fig. 4 is a fragmentary vertical section taken on a vertical plane substantially midway between the sides of Fig. 1.

Fig. 5 is a fragmentary somewhat enlarged elevation at the rear of the left hand side of Fig. 1.

Fig. 6 is a fragmentary detail in elevation illustrating the hinged connection of bars to which sectors of the table top are hingedly connected.

Fig. 7 is a fragmentary vertical section substantially on a plane corresponding to line 7—7 of Fig. 1, and

Fig. 8 is a fragmentary vertical section substantially on the plane of line 8—8 of Fig. 3.

Like reference characters refer to like parts in the different figures of the drawings.

In the construction shown are three vertical supporting legs 1, 2 and 3. The legs 1 and 2, which may be termed outer legs, are connected adjacent their upper ends by a curved rail or apron 4. Bars 5 extend between each of the legs 1 and 2 and the inner leg 3 a short distance below the upper ends of said legs. A flat bar 6 extends from the inner leg 3 outwardly to substantially the middle point of the curved apron 4 (Fig. 3). The legs 1, 2 and 3, the bars 5 and 6 and the apron 4, are rigidly secured together, making a rigid frame.

A horizontal sector 7 of a top is located over the upper ends of the legs 1, 2 and 3 and over the upper edge of the apron 4, and is permanently secured thereto. Such sector 7 supplies one-quarter of the complete table top. Two sectors 8, each one-half the width of the sector 7, are hingedly connected at their outer edges to the outer edges of sector 7 and are adapted to be folded over to lie upon the part 7, as shown in Fig. 1. The hinges indicated at 8a in Figs. 2 and 7 are of a concealed type which do not show from above when the parts 8 are folded outwardly through an arc of 180° to lie in the same plane with the part 7. When thus outwardly unfolded, one-half of the table top is provided.

Two horizontal bars 9 and 10 are hingedly connected at adjacent ends by a hinge 11, which has a vertical hinge pintle 11a extended downwardly (Figs. 4 and 6) below the hinge. The hinge 11 is located at the rear of the center leg 3, which at its upper end is recessed as at 12, to provide space for entrance of the hinge when the parts of the table are drawn together, as will hereafter appear. A board 13 of the shape best shown in Fig. 3, is connected to the bar 9 and extends forwardly therefrom and has an outer curved edge with which is connected a curved rail 14. Similarly, a board 15 is secured to the bar 10 and extends forwardly therefrom, has a curved edge and a curved rail 16 connected therewith. The radius of the rail 16 is less than that of the rail 14 and the board 15 is located in a higher plane than the board 13, whereby the two bars 9 and 10 may be swung inwardly toward each other about the axis of the hinge pintle 11a, so as to bring said bars 9 and 10 into substantial parallelism with the frame bars 5, and as shown in Fig. 4, with the parts 15 and 16 located over the part 13 and with the curved rail 16 within the curved rail 14. Rollers 17 mounted upon suitable brackets are connected to the front outer end portions of the rails 14 and 16, (Fig. 8) and are adapted to bear against the under side of the top sector 7. When swung out-

wardly, so as to bring the bars 9 and 10 in horizontal alignment, as in Figs. 2 and 3, the brackets which carry the rollers 17 come against stops 18 connected to the under side of the top member 7, thus limiting the outward movement of the bars 9 and 10 and causing them to be stopped when in alignment with each other at the time that the rollers 17 engage against the stops 18.

A bar 19 (Figs. 3 and 4) is connected at its rear end to the lower end of the extended pintle 11a and passes forwardly through a horizontal opening in the leg 3. Its front end has pivotal connection to a rod 20 which extends in a forward direction underneath the bar 8, and at its front end is connected to a hand lever 21 pivotally mounted at one end on a bracket 22 secured to the under side of the bar 8 (Fig. 3). The connection of the rod 20 to the hand lever 21 is at a short distance from the pivot of the hand lever. Swinging the hand lever in a clockwise direction thereupon causes the rod 20 and bar 19 to be moved longitudinally and thus moves the hinge 11, the connected bar 10 and the members 13, 14, 15 and 16 secured thereto forwardly. In this movement it will be noted that the brackets carrying the rollers 17, engaging against the inner sides of the stops 18, may be moved directly forward, the sides of the stops 18 being parallel to each other and parallel to the forward direction of movement imparted to the bar 10, hinge 11 and associated and connected parts.

A top sector or quadrant 23 is hingedly connected by hinges 24 to and at the rear of the bar 9. Similarly, a like top sector 25 is hingedly connected by hinges 24 to the rear portion of the bar 10. The two quadrants 23 and 25 at their meeting edges are hingedly connected by hinges shown at 24a in Fig. 5. When the bars 9 and 10 have been moved outwardly into horizontal alignment with each other, as in Fig. 2, the two top sectors 23 and 25 are in the same plane and may then both together be lowered to a horizontal position, as in Fig. 2.

Each of the top sectors 23 and 25 is designed to be supported by a vertical leg 26 pivotally mounted at its upper end on a bracket 27, secured to the under side and toward the outer curved edge of its associated top sector. The legs are releasably retained in vertical position or in folded position by spring members 28. The movement of the two top sectors 23 and 25 to horizontal position is with the hand lever 21 released, whereby ample space is provided so that the parts 8 may afterward be turned outwardly. Then the table top is closed by swinging the hand lever 21 in a clockwise direction, drawing the parts snugly together. It will be observed that the rod 20 will pass from one side to the other of the center of the pivot about which the hand lever 21 turns, and thus there is provided a secure lock against separation of the parts of the table top.

Cooperating interengaging spring catches 29 and 30 on the bars 9 and 10 and 5, shown in Fig. 3, are provided so that when the bars 9 and 10 are swung forwardly the catches 29 thereon will engage with the cooperating catch members 30 on the bars 5, to hold the bars 9 and 10 against accidental rearward movement.

When the construction is in its retracted and folded form as in Fig. 1, the top sections 8 are folded over and lie upon the underneath section 7, the top sectors 23 and 25 are in vertical position and have been turned, through their hinge connections at 24a, to lie at right angles to each other. The bars 9 and 10 have been swung for-

wardly so that the interengaging catches 29 and 30 are in operative engagement. The legs 26 are folded against the rear sides of the top members 23 and 25, as in Fig. 5. In such position the structure is adapted to be placed in a corner of a room where it will occupy small space and the horizontal top provided by the two members 8 may be readily used as a desk top or the like.

When the structure is to be converted into a table, the first operation after the structure has been brought out into the middle part of the room, is to swing the two top sectors 23 and 25 into alignment with each other. This will disengage the catches 29 and 30 and move the bars 9 and 10 into alignment with each other. Such movement is stopped when the brackets carrying the rollers 17 come against the stops 18. The two hinged together sectors 23 and 25 are then turned downwardly to horizontal position, the supporting legs 26 having first been turned so as to take a vertical position to support the sectors when they reach horizontal position. The parts 8 are then turned outwardly. When this has been done, between the adjacent edges of the parts 8 and the forward edges of the sectors 23 and 25 there will be a gap or space which is closed by grasping the handle 21 and moving it counterclockwise to the position in Fig. 3. Said gap is closed and the parts drawn together with cooperating pins or pegs shown best in Figs. 2 entering the corresponding sockets or recesses to receive them in the adjacent parts of the top. The return to the position shown in Fig. 1 is by reversal of these movements, first releasing the lock by turning the handle member 21 counterclockwise, then swinging the parts 8 over onto the underneath top section 7, after which the two sectors 23 and 25 are turned to vertical position, and then swung to the position shown in Fig. 1 at right angles to each other, with an automatic interengagement of the catches 29 and 30 as they reach their final positions. Of course the supporting legs 26 are folded, as in Fig. 5, against the adjacent sides of their associated top members 23 and 25.

The construction described is very practical and useful, is readily manufactured and assembled and is very easily converted to occupy the small space shown in Fig. 1, or the larger space where it is a table with a horizontal top, as in Fig. 2. While the disclosure shows a table of circular outline with the several parts 7, 8, 23 and 25 as sectors of a circle, it is to be understood that said parts 7, 8, 23 and 25 are not necessarily restricted to outer curved edges in the arc of a circle, but may be of a different shape and outline than shown. For example, the sections of the table top may be designed so that the completed table top will be rectangular or square in outline. Likewise the outer edges may be of scalloped or other and different forms without departing from the invention.

The invention is defined in the appended claims and is to be considered comprehensive of all forms of structure coming within their scope.

I claim:

1. In a construction of the class described, a support including vertical supporting legs located substantially at the apices of a triangle, connections between said legs, a top section comprising substantially one-quarter of the area of a table top fixedly secured to and over the legs, other top sections each one-half the area of the first top section hinged at the side edges thereof, and adapted to fold thereover or be unfolded to lie

in the same horizontal plane therewith, two additional top sections hingedly connected together at one edge, horizontal bars hingedly connected together adjacent their meeting ends, to each of which one of said two additional top sections is hingedly connected, said bars being adapted to be moved into alignment with each other and thereby locate said additional top sections in the same plane, whereupon they may be turned 5 downwardly to a horizontal position, each of said additional top sections having an area equal to one-fourth of the top and when in horizontal position completing the top, and a foldable leg connected to each of said additional top sections 10 adapted to be turned to vertical position when the additional top sections are disposed in horizontal position.

2. A construction containing the elements in combination defined in claim 1, combined with a 20 rod connected with said hinge, and manually operable means for drawing said rod longitudinally to bring said additional top sections against adjacent top sections when unfolded to a horizontal plane and retain them against each other in close 25 edge engaging relation, as specified.

3. In a table, an inner and two outer spaced apart vertical supporting legs located substantially at the apices of a triangle, bars connecting the inner leg with said outer legs, said bars being 30 located a short distance below the upper ends of said legs, a member extending between and connecting said outer supporting legs, a top section located over and permanently secured at the upper ends of the legs, said top section being substantially one-quarter of the area of a complete 35 table top, other top sections hinged one to each side edge of the first top section, each having an area of one-eighth of the complete table top and adapted to be both folded onto the first top 40 section and lie thereover or unfolded to lie in the same horizontal plane therewith, two horizontal bars hingedly connected at their adjacent ends, said hinge lying adjacent but back of the inner supporting leg, said hingedly connected bars being 45 adapted to be turned to one position where they are in longitudinal alignment and to another position where they parallel the first mentioned bars, an additional top section hingedly connected at the rear edge of each of said hinged bars, 50 means for hingedly connecting said additional top sections at their adjacent edges, each of said additional top sections having an area of one-fourth of the complete table top, said hingedly connected bars when moved into longitudinal alignment carrying the top sections hinged thereto into a common plane whereby they may be 55 turned from a vertical position to a horizontal position or vice versa, and when in vertical position may be moved with the hinged bars to which 60 attached to lie at an angle to each other and against the edges of the first fixed top section.

4. A construction containing the elements in combination defined in claim 3, combined with a member attached to each of said hinged bars 65 adjacent its outer end and extending underneath the fixed top section, and a roller secured at the free end of each of said members to ride against the under side of the first top section, said members being movable inwardly toward each other 70 when the hinged bars are swung toward each other.

5. A construction containing the elements in combination defined in claim 3, combined with a curved member connected adjacent the outer end 75 of each of said hinged bars and extending, one

over each of the connecting bars between the inner and outer legs, a horizontal plate secured to each of said hinged bars and to its associated curved member, and rollers mounted at the free ends of each of said curved members bearing 5 against the under side of the fixed top section.

6. A construction containing the elements in combination defined in claim 3, combined with a bar extending between and connected at its ends to the inner leg and to the connecting member between the outer legs, a rod secured at one end to said hinge, and a manually operable lever pivotally mounted at one end on said last mentioned bar, said rod having a connection to said handle a short distance from its point of pivotal connection, whereby on turning the handle in one direction, the rod is moved longitudinally to move the hinge and the bars hingedly connected thereby in a forward direction.

7. A table construction comprising, a horizontal top section having an area substantially equal to one-quarter of the area of a complete top, supporting means fixed thereto, two additional top sections each having an area of substantially one-fourth of the area of the complete top 20 hingedly connected together, means associated therewith comprising two bars hingedly connected together end to end, one of said additional top sections being hinged to each of said bars whereby said additional top sections when the hinged bars are in alignment with each other are located in a common plane and may be turned to either a vertical or a horizontal position, and in vertical position turned to lie at right angles 25 to each other and against the edges of the first top section, means operatively connecting the additional top sections to the first top section and its supports, and two other top sections, each one-half the area of the first top section adapted to lie thereover or to be located in a horizontal plane between its side edges and said additional top sections, as specified.

8. In a table, a horizontal top section, two other top sections, each one-half the area of the first top section adapted to lie thereover or to be located in the same horizontal plane therewith, two additional top sections each of the same area as the first top section hingedly connected together at one edge of each thereof, means to which said additional top sections are hingedly connected whereby the additional top sections when lying in the same plane may be turned to either vertical or horizontal positions and when in vertical position may be turned to lie at right angles to each other and against the side edges of the first top section, supporting means for the first top section rigidly connected thereto, and a supporting means for each of said additional top sections pivotally connected thereto to lie thereagainst when said additional top sections are in vertical position and to extend downwardly therefrom when in horizontal position.

9. In a table, a top section having side edges converging toward and meeting at a point, supporting legs permanently connected thereto, two other top sections, each one-half the area of the first top section adapted to lie thereover or to lie in the same horizontal plane therewith against its side edges, two horizontal bars adapted to be located in alignment underneath the outer edge 70 portions of said additional top sections when located in the same plane with and against the first top section, means for hingedly connecting the horizontal bars together at their inner adjacent ends, means for mounting said horizontal 75

bars on the support of the first top section whereby they may be swung inwardly into positions paralleling the side edges of said first top section, and an additional top section hingedly connected to the rear portion of each of said horizontal bars.

10. A construction containing the elements in combination defined in claim 9, each of said additional top sections having an area substantially

equal to that of the first top section, means hingedly connecting the adjacent edges of the two additional top sections together, and a supporting leg pivotally connected to the under rear side of each of said additional top sections adapted to be folded thereagainst or to be turned outwardly at right angles thereto. 5

THURLOW E. McFALL.
